UNITED STATES PATENT OFFICE

2,611,687

HOOD ORNAMENT CONSTRUCTION

Raymond L. Logue, Detroit, Mich., assignor to
 Kaiser-Frazer Corporation, Willow Run, Mich.,
 a corporation of Nevada

Application June 9, 1950, Serial No. 167,215

1 Claim. (Cl. 41—10)

1

The present invention relates to improvements in an assembly of a plurality of parts, and improved means for holding such parts in assembled relation; and, particularly, relates to improvements in hood-ornament assemblies and the means for securing the assembled parts together.

Hood ornament assemblies comprise a base having a surface complementary in shape to that of the hood to which the assembly is attached, and the hood assembly of the present invention is formed of a plurality of separate parts which are assembled and secured together. An ornamental member is secured to the base and such ornamental member has an elongated projection formed on the under surface thereof which is received within an elongated opening in the base. The parts are held together by means of a removable spring clip of novel construction which has a pair of parallel legs received within a groove formed in the projection within the opening of the base and engaging the walls of the groove, and a shoulder on the base to lock the parts against separation. The clip is readily accessible from the under side of the base so that the parts may be easily assembled or disassembled.

One of the primary objects of the present invention is to provide a simplified means for securing a pair of members in assembled relation.

A further object of the invention is to provide a simplified and resilient means for securing a pair of parts in assembled relation so that the parts are securely held together and rattles therebetween will not develop in use.

Other objects of the invention will become apparent from the following specification, the drawing relating thereto, and from the claim hereinafter set forth.

In the drawing, in which like numerals are used to designate like parts in the several views throughout:

Figure 1 is a side elevational view of a hood ornament embodying features of the present invention, and illustrating such ornament on an automobile hood.

Fig. 2 is a cross-sectional view taken substantially along the line 2—2 of Fig. 1.

Fig. 3 is an elevational view of a portion of the under side of the base, taken along the line 3—3 of Fig. 1 and illustrating the assembly.

Fig. 4 is a perspective view of a novel form of holding clip forming a part of the present invention.

Referring to the drawing, a hood ornament,

generally indicated at 1, is illustrated as mounted upon an automobile hood 2. The hood ornament 1 comprises an elongated metal base 3 having the under surface thereof curved to conform to the curvature of the top surface of the hood 2 in the region to which it is to be applied. Such base 3 is hollowed out on the under side thereof to provide a longitudinally extending groove 4 therealong which communicates within the forward portion thereof with an elongated opening 5.

An ornamental ring 6, which may be formed of a transparent plastic, is mounted to the base 1 and is received within a depression 7 formed in the forward portion thereabove with the rear edge of the ring 6 abutting against a shoulder 8 formed on the base. The ring 6 is secured to the base through the cooperation of an integral elongated projection 9. The projection 9 is complementary in shape to the shape of the opening 5 so that lateral and longitudinal movement of the ring 6 is prevented. In order to prevent disassembly of the parts, the projection 9 is formed with a pair of longitudinally extending grooves 10 which are formed on opposite sides of the projection 9 along the length thereof.

The base 3 is formed with a pair of longitudinally extending shoulders 11 within the opening 5 and adjacent the grooves 10, with such shoulders 11 facing away from the ring 6.

The opening 5 and the groove 4 are in open communication; that is, the opening 5 forms a continuation of the groove 4 and that portion of the base 2 adjacent opening 5 is of gradually decreasing depth from front to rear, as shown in Fig. 1.

The ring 6 and the base 3 are held together by means of a spring clip 12. The spring clip 12 is generally U-shaped and substantially flat and is formed of a spring metal. The clip 12 has a pair of longitudinally extending and parallel legs 13 which are transversely flat, and which are formed with longitudinally extending spring waves substantially normal to the flat surfaces thereof. When the clip is assembled, the wave legs provide a resilient connection between the ring 6 and base 3.

The ring 6 is assembled to the base 3 by the insertion of the projection 9 within opening 5, as best shown in Fig. 2. The clip 12 is then inserted by moving it along groove 4 toward the front of the assembly, and so that the legs 13 are sprung into the grooves 10 engaging the sides of the grooves and projecting beyond the sides of the projection, so that the legs 13 also engage shoulders 11. The relative dimensions and pro-

portions of the legs 13 and the grooves 10 and shoulders 11 are such that the clip is forced into its assembled position so that the legs 13 are sprung, and exert a resilient force against the grooves 10 and the shoulders 11 so that the ring and base are securely held together.

If it becomes necessary to disassemble the parts; for example, if the ring were broken, this may be accomplished in a relatively easy way by removing the hood ornament, and the base of the clip 12 is then exposed within groove 4 so that it may be pulled out and the new ring replaced.

The particular hood ornament here disclosed also includes an additional ornamental member 14 which is substantially circular in cross section, tapering from end to end. The intermediate portion of the ornamental part 14 is supported on a complementary surface on base 3 and is secured thereto by screws 15. The forward end of the portion 14 extends through the ring 6, as shown in Fig. 2.

Formal changes may be made in the specific embodiment described without departing from the spirit of the invention, the scope of which is commensurate with the appended claim.

What is claimed is:

An assembly comprising first and second members, one of said members having an elongated opening therein, the other of said members having a complementary projection received within said opening, means providing a pair of longitudinally

extending grooves within said opening in and along the opposite sides of said projection, means forming a pair of longitudinally extending shoulders within said opening on the other of said members adjacent said grooves and on opposite sides of said projection, and a resilient U-shaped locking member having a pair of elongated transversely flat parallel legs received within said grooves and against said shoulders to hold said first and second members together, said legs being distorted in longitudinally extending spring waves to resiliently engage said grooves and shoulders and prevent separation of said first and second members.
